BUCKET FOR EXCAVATING EQUIPMENT

Tage Nils Wilhelm Leijon, Stocksund, Sweden

Filed Dec. 22, 1965, Ser. No. 288

Claims priority, application Sweden June 24, 1965

Term of patent 14 years

(Cl. D14—3)

FIGURE 1 is a front perspective view of a bucket for excavating equipment showing my new design,

FIGURE 2 is a perspective view as seen from the bottom of FIG. 1,

FIGURE 3 is a perspective view as seen from the top of FIG. 1, and

FIGURE 4 is an elevation view as seen from the rear of FIG. 1.

I claim:

The ornamental design for a bucket for excavating equipment, as shown.
